HYDRAULIC JACK

Timothy C. Pomeroy, Long Beach, Calif.

Original application January 22, 1938, Serial No. 186,366, now Patent No. 2,211,479, dated August 13, 1940. Divided and this application July 5, 1940, Serial No. 343,928

1 Claim. (Cl. 60—52)

This invention relates to new and useful improvements in hydraulic jacks, and is a division of my pending application, Serial No. 186,366, now Patent No. 2,211,479.

An object of the present invention is to provide a hydraulic jack having means embodied in the construction thereof, whereby it may be operated in any position from a vertical to a horizontal position.

A further object is to provide a hydraulic jack comprising a main cylinder, a reservoir, and an expansion tank, so interconnected that the fluid may be circulated therebetween without the provision of air vents, as is now common practice in most fluid-operated jacks.

A further object of the invention is to provide a hydraulic jack comprising a cylinder, a reservoir, and an expansion tank and in which the expansion tank serves a dual purpose, in that when the plunger of the jack is lowered to its normal, or contracted position, the expansion tank acts to receive the overflow from the reservoir, and when the jack is operated to lift a load, a vacuum is created in the reservoir, which draws the liquid from the expansion tank into the reservoir, against the force of gravity, because of the circulatory connection between the expansion tank and reservoir being at their upper ends, and whereby the vacuum in the apparatus becomes greater, as the jack is operated to lift the load, which materially aids in sealing off the outside atmosphere from the liquid in the jack, because of the vacuum tending to draw the packing glands of the jack into tighter contact with their respective parts.

Features of the invention reside in the flexible conduits provided in the expansion tank and reservoir, having weighted heads at their free, unsupported ends adapted to bend said conduits, when the jack is supported at an incline or in a horizontal position, whereby the intake ends of said conduits will be disposed below the level of the liquid in said tank and reservoir, when the jack is supported on its side, or in substantially a horizontal position; in the provision of a hydraulic jack comprising a reservoir and an expansion tank, neither one of which is provided with a vent opening, whereby the jack may be placed on its side without danger of the liquid leaking therefrom; and, in the provision of a hydraulic, leak-proof jack of simple and inexpensive construction.

Other objects of the invention will appear from the following description and accompany-

ing drawings and will be pointed out in the annexed claim.

In the accompanying drawings there has been disclosed a structure designed to carry out the various objects of the invention, but it is to be understood that the invention is not confined to the exact features shown as various changes may be made within the scope of the claim which follows.

In the drawings:

Figure 1 is a vertical sectional view substantially on the line 1—1 of Figure 3, showing the construction of the main cylinder and plunger and the means for supporting the operating handle on the base;

Figure 2 is a vertical sectional view substantially on the line 2—2 of Figure 1, showing the means provided within the expansion tank and reservoir, whereby the jack may be operated in a horizontal position, or at any desired angle;

Figure 3 is a sectional plan view on the line 3—3 of Figure 1, showing the arrangement of the main cylinder, expansion tank and reservoir on the pump base;

Figure 4 is a detail sectional view on the line 4—4 of Figure 1, showing the valve means in normal closed position;

Figure 5 is a similar view, but showing the pump piston actuated to open the valves;

Figure 6 is a detail sectional view on the line 6—6 of Figure 5;

Figure 7 is a plan view of the jack on a smaller scale, showing various positions of the operating handle of the pump; and

Figure 8 is a view showing the positions assumed by the flexible tubes in the expansion tank and reservoir, when the jack is placed in a horizontal position.

The novel jack herein disclosed is shown comprising a base, generally indicated by the numeral 2, preferably having a counterbore 3 therein, adapted to receive the lower end of a main cylinder 4. The lower end of the cylinder has secured therein a plug or closure member 5 having a depending cylindrical portion 6 adapted to be received in a relatively smaller counterbore 7, axially aligned with the main cylinder.

The upper end of the cylinder is shown closed by means of a sealing member 8 having a conical surface 9 adapted to engage a correspondingly shaped seat 11 provided at the upper edge of the cylinder wall. The member 8 has an inwardly extending flange 12 bored to receive the plunger 13, which is tubular, as clearly illustrated in Figures 1 and 3. A suitable packing 14

is seated on the flange 12. A gland 15 is seated against the upper face of the packing 14 and is adapted to be forced downwardly by a cap 16, received in threaded engagement with the upper end of the cylinder, as clearly illustrated in Figure 1. The cap 16 is bored to receive the reduced upper end 17 of the gland 15, and the gland, in turn, is bored to receive the plunger 13 and cooperates with the member 12 to guide the upper end of the plunger in its reciprocal movement.

A load-engaging element 18 is fitted into the upper end of the plunger 13 and provides a cap therefor. The lifting element is provided with a threaded socket for receiving the upper end of a tie rod or bolt 19, the lower end of which is exteriorly threaded to receive a nut 21.

A plunger head, generally indicated by the numeral 22, is secured to the lower end of the plunger 13, and is shown comprising a disk-like member 23, preferably having a shallow counterbore in its upper surface for receiving the lower end of the plunger 13. A cup-shaped packing 24 is seated against the bottom face of the member 23, and is preferably provided with a suitable retainer 25, of resilient material, for yieldably holding the peripheral flange of the packing 24 in sealing contact with the walls of the cylinder 4. A suitable washer 26 is interposed between the retainer 25 and the nut 21, whereby the horizontal wall of the packing may be tightly clamped against the member 23 by rotation of the nut 21.

A suitable relief valve 27 is provided in the lowermost end of the tie rod 19 of the plunger and is normally retained on its seat by a suitable spring element 28, secured to the lower terminal of the rod 19 by suitable screws, as illustrated in Figure 1. A fluid duct 29 leads from the valve 27 to a transverse opening 31 provided in the rod 19, immediately above the member 23. Suitable openings 32 are provided in the wall of the plunger 13 at its lower end and are aligned with the opening 31 in the rod 19.

An actuating bar 33 is received in the aligned openings 31 and 32, and has its ends disposed in close proximity to the walls of the cylinder 4. The actuating bar 33 rests upon the upper end of a pin 34, whose lower end engages the relief valve 27. The means 28 for yieldably holding the relief valve 27 on its seat has sufficient tension to overcome the weight of the actuating bar 33 and pin 34 so as to normally hold the valve 27 on its seat, as will readily be understood by reference to Figure 1. The purpose of the relief valve 27 will subsequently be described.

An important feature of the present invention resides in the fluid retaining means of the jack which, as best illustrated in Figures 2 and 3, comprises a reservoir 35 and an expansion tank 36, interconnected at their upper ends by a suitable by-pass or cross duct 37, provided in a cap 38 preferably having annular grooves 39 in its lower face adapted to receive the upper ends of the expansion tank 36 and reservoir 35, as clearly illustrated in Figure 2. Suitable gaskets 41 are seated in the bottoms of the grooves 39 and are engaged by the upper ends of the expansion tank and reservoir to prevent leakage therebetween.

The lower ends of the reservoir and expansion tank 35 and 36 are shown seated on gaskets 42 supported in shallow counterbores provided in the base 2. Suitable tie rods 43 are shown extending lengthwise through the expansion tank 36 and reservoir 35, and have their lower ends received in threaded engagement with the base 2,

as clearly illustrated at 44 in Figure 2. The upper ends of the tie rods 43 are received in apertures provided in the cap 38, and preferably have heads 45, whereby the rods 43 may be conveniently rotated to securely fasten the expansion tank and reservoir to the base in leak-tight relation.

The means for controlling the circulation of fluid to and from the main cylinder is best illustrated in Figure 1, and comprises a pump, generally indicated by the numeral 46. The pump comprises a cylinder 47 having a suitable base 48 fitted to and secured to the base 2 of the jack by suitable bolts 49, best illustrated in Figures 4 and 5. The pump cylinder 47 has a piston 51 mounted for reciprocal movement therein, which projects from the upper end of the cylinder. Leakage is prevented around the piston by a suitable gland 52 and packing 53, received in a counterbore 54 in the upper end of a cylinder and secured therein by a suitable cap 55, received in threaded engagement with the upper end of the cylinder 47. A suitable locking nut 56 is also received in threaded engagement with the upper end of the cylinder 47. This nut secures the cap 55 in adjusted position, whereby the desired sealing engagement between the packing glands 52 and 53 and the piston 51 may be obtained.

Means is provided in the lower portion of the pump for controlling circulation of the fluid therethrough. As best illustrated in Figures 4 and 5, the bore 57 of the cylinder communicates at its lower end with oppositely disposed, axially aligned valve chambers 58 and 59. A suitable check valve 61 is mounted in the valve chamber 58 and normally closes the upper end of a port 62. A spring 63 is preferably provided for constantly urging the valve 61 into engagement with its seat. The lower end of the port 62 communicates with one end of a horizontal duct 64, the opposite end of which is in direct communication with one end of a flexible intake tube 65, whose lower end is secured to the base 2 by a suitable fitting 66. The flexible tube 65 extends upwardly into the reservoir 35 and has a weighted head 67, the upper end of which terminates at or near the intermediate portion of the reservoir 35. The flexible tube 65 forms an important part of the present invention, as will be subsequently described.

50 A check valve 68 is also provided in the valve chamber 59, and is normally engaged with a seat 69 by a suitable spring 71. A vertical duct 72 has its upper end communicating with the valve chamber 59 and its lower end with one end of a horizontal duct 73, whose opposite end is in direct communication with a duct 74. The duct 74 is connected at its opposite end to an annular passage 75, provided in the lower reduced portion 6 of the member 5 of the main cylinder 4. One or more transverse ducts 76 are provided in the reduced portion 6 of the lower end of the main cylinder, and are in direct communication with the annular channel 75 provided therein. A small duct 77 establishes communication between the transverse duct 76 and the counterbore 78, provided in the member 5 of the main cylinder. This counterbore is in communication with the lower end of the cylinder beneath the piston head 22, so that when fluid is pumped into the lower end of the cylinder beneath the head 22, the latter will be elevated, as will readily be understood.

Means is provided for operating the pump piston 51 and also, whereby said piston may be locked against axial movement to prevent lowering of

the plunger 13, when supporting a load. As shown in Figure 1, the upper end of the pump piston 51 is pivotally connected to a member or head 79, by a horizontally disposed pivot pin 80. An operating handle 81 is secured at one end to the member 79. A connecting element 83 has one end pivotally connected to the head 79 by a vertically disposed pivot pin 86. The axis of the pivot pin 86 intersects the axis of the pivot 80, and the latter provides the axis about which the head 79 swings. The opposite end of the element 83 is preferably forked, as shown in Figures 1 and 2, and said forked end is pivotally connected to the upper end of an arm 84, by a horizontally disposed pin 90. The lower end of the arm 84 is pivotally mounted on the base 2 of the jack substantially between the expansion tank 36 and reservoir 35, as clearly illustrated at 85.

The above described mechanism provides a pivotal support for the handle 81 and also a locking means whereby the piston may be locked against rotary movement, thereby to prevent accidental actuation of the valve mechanism, when the jack is supporting a load. To thus lock the piston against rotary movement, the operating handle 81 is moved to an inclined position, either above or below the horizontal, as indicated by the dotted lines in Figure 1, whereby the handle cannot be swung to a lateral position, as shown in full and dotted lines in Figure 7, to relatively rotate the piston and thereby unseat the check valves 61 and 68.

Thus, it will be seen that the operating handle 81 has the dual function of operating the piston 51 and also unseating the valves to release the fluid from the lower end of the cylinder. This is a very desirable feature in that it necessitates but a single operating member for performing these two functions.

To operate the piston 51, the operating handle 81 must be substantially in its intermediate or horizontal position, as shown in full lines in Figure 1 and the dotted lines C in Figure 7. When thus positioned, the axes of the pivots 80 and 90 are disposed in parallel relation, whereby the head 79 of the handle and the connecting element 83 may be oscillated about the axis of the pivot 90, as a single unit. By thus oscillating the head 79 and element 83 about the axis of the pivot 90, reciprocatory movement is imparted to the piston 51, as indicated by the full and dotted lines in Figure 1.

The above described locking means eliminates all danger of the plunger lowering under a load, because of the fluid accidentally being released from the lower end of the cylinder 4. If desired, suitable means, not shown, may be provided for positively securing the handle in locking position.

Means is provided for actuating the valves 61 and 68 in the lower portion of the pump, whereby these valves may be forcibly unseated, thereby to permit the fluid to return from the lower end of the cylinder beneath the piston head 22, to the reservoir 35.

To thus open the valves 61 and 68, a pair of thrust elements 87 and 88 are mounted in the valve chambers 58 and 59, respectively, and each normally has one end projecting into the bore 57 of the cylinder 41, as best illustrated in Figure 4. These thrust members are spring-actuated, and are preferably tubular, as shown. Each has a suitable spring 89 mounted therein, and the inner ends of these springs engage pins 91 secured in the adjacent ends of the thrust mem-

bers, as best illustrated in Figure 4. The opposite ends of the springs 89 are seated against pins 92 having their terminals supported in a pair of fixed sleeves 93 and 90' of the valve chambers 58 and 59, respectively. The outward terminals of the thrust members 87 and 88 are preferably beveled, as shown, whereby said ends may readily be inserted between the check valves and their respective seats, when the thrust members are moved in opposite directions, by the lower end of the piston 51, as will readily be understood by reference to Figure 6. The valve 61 is preferably opened slightly in advance of the valve 68.

As shown in Figures 4 and 6, the piston 51 has its lower end portion 94 flattened, whereby when the piston 51 is turned to the position shown in Figure 5, the thrust members 87 and 88 will be thrust outwardly. When these members are thus thrust outwardly, their outer ends will engage the check valves 61 and 68 and unseat them, as clearly illustrated in Figure 5. When the flattened terminal 94 of the piston 51 is returned to its normal position, as shown in Figure 4, the thrust members 87 and 88 will return to their normal positions by the action of the springs 89, and thus permit the valves 61 and 68 to return to their respective seats, and thereby render the pump operative to pump fluid from the reservoir into the lower end of the cylinder 4 beneath the piston head 22.

Means is also provided for establishing communication between the upper end of the cylinder 4 and the lower end of the reservoir 35, and comprises a relatively small tube 95 having its upper end connected to the interior of the cylinder 4 by a suitable fitting 96. The lower end of the tube 95 has a suitable fitting 97 connecting it to one end of a horizontal duct 98 provided in the base 2 of the jack. The opposite end of the duct 98 communicates with the lower end of the reservoir 35, as clearly illustrated in Figure 3.

Another feature of the invention resides in the provision of a flexible tube 100 within the expansion tank 36, which has its upper end secured to the head 38 by a suitable fitting 99. This fitting is in direct communication with the by-pass 37 in the head 38, which establishes communication between the interiors of the reservoir 35 and the expansion tank 36. The lower end of the flexible tube 100 has a weighted head 101 whose lower end is disposed in close proximity to the bottom wall of the expansion tank, as best illustrated in Figure 2.

Before operating the jack, enough fluid is introduced into the jack to completely fill the reservoir 35 and partially fill the expansion tank 36, when the plunger head 22 is in its lowermost position, as shown in Figure 1. The jack handle 81 is then oscillated in substantially a vertical plane, whereupon fluid is drawn into the pump cylinder 41 from the reservoir 35 through the ducts 62 and 64. When the piston 51 is thrust downwardly, the fluid drawn into the pump cylinder through the valve 61 is forced through the valve chamber 59, thereby unseating the valve 68. From the valve chamber 59, the fluid flows through the ducts 72, 73 and 74, into the lower end of the main cylinder 4, as will readily be understood. Upon continued oscillation of the handle 81, the fluid will continue to flow into the lower end of the cylinder 4 beneath the plunger head 22, thereby causing the plunger 13 to elevate the load, until the operation of the pump is interrupted.

If the operator fails to cease pumping, when the plunger approaches the limit of its upward movement, the actuating bar 33, carried by the plunger, will subsequently engage the bottom surface of the member 12, whereby the bar 33 is moved downwardly relatively to the plunger, and thereby unseats the release valve 27. Such actuation of the release valve will permit the fluid pumped into the cylinder beneath the piston head 22, to by-pass or escape through the port 29 in the piston head, into the cylinder above the piston head, whence it returns to the reservoir 35, through the tube 95.

If the operator continues to oscillate the pump handle, a portion of the fluid returned to the reservoir may, when the reservoir is subsequently filled, by-pass over into the expansion tank through the horizontal duct 31 provided at the upper ends of the expansion tank and reservoir.

From the foregoing, it will readily be understood that the herein described jack is substantially fool-proof in operation, because, by the provision of the reservoir 35 and expansion tank 36, there is very little danger of the jack becoming inoperative because of the lack of fluid pressure. There is always enough fluid in the apparatus to assure efficient operation thereof provided, of course, that the fluid contained in the jack does not escape or leak therefrom. Leakage of the liquid from the apparatus is substantially eliminated as a result of the vacuum which is created in the apparatus, when the jack is operated to elevate a load. This vacuum becomes greater as the jack is operated to lift the load, and thereby tends to draw the packing glands into tighter sealing engagement with their respective parts, whereby the liquid cannot escape from the jack, even when the jack is supporting a heavy load.

The flexible tubes 65 and 100 provided in the reservoir 35 and expansion tank 36, respectively, provide means whereby the jack may be operated at any angle, or in a horizontal position, as illustrated in Figure 8. In this figure, it will be seen that when the jack is placed in a horizontal position, the tubes 65 and 100 will bend or flex by gravity, whereby their weighted heads will rest upon the lowermost portions of the walls of the reservoir and expansion tank. There is sufficient oil in the reservoir so that the level of the oil therein, when the jack is placed in a horizontal position, will be substantially above the head 67 of the intake tube 65. The flexible

tubes 65 and 100, therefore, greatly extend the usefulness of the jack in that they make it possible to operate the jack, when placed at an angle, or when in a horizontal position which, heretofore, has been impossible with hydraulic jacks of conventional construction.

The lower end of the flexible tube 100 is disposed in close proximity to the bottom of the expansion tank, so that as the fluid is pumped from the reservoir into the lower end of the main cylinder, in the operation of elevating the plunger 13, a portion of the fluid in the expansion tank may be drawn upwardly through the tube 100 and into the reservoir by the vacuum 15 which is created in the upper portion of the reservoir above the level of the fluid therein. The reservoir and expansion tank are so proportioned that there is ample room for the transfer of the fluid therebetween and to and from the main cylinder, without requiring the use of air vents. This is a very desirable feature in that it eliminates all danger of oil leakage from the jack, when not in use, regardless of the position of the jack.

I claim as my invention:

In a hydraulic jack, a cylinder, a plunger therein, an inelastic fluid, a reservoir, a valved passage connecting the bottom of reservoir to the cylinder, an expansion tank disposed adjacent to the reservoir, a fluid passage connecting the upper ends of the reservoir and expansion tank, a pump for pumping fluid from the reservoir through the valved passage to the cylinder to elevate the plunger, the intake of said valved passage having one end of a flexible tube connected thereto, said tube being mounted in the bottom of the reservoir and extending upwardly therein and having a weighted head, whereby the tube will flex or bend when the jack is placed 25 in an inclined or horizontal position, thereby to retain the intake end of said flexible tube beneath the level of the fluid in the reservoir, and the fluid passage connecting the upper ends 30 of the reservoir and expansion tank having a passage having one end of a flexible tube connected thereto, said tube being mounted in the bottom of the reservoir and extending upwardly therein and having a weighted head, whereby the tube will flex or bend when the jack is placed 35 in an inclined or horizontal position, thereby to retain the intake end of said flexible tube beneath the level of the fluid in the reservoir, and the fluid passage connecting the upper ends 40 of the reservoir and expansion tank having a passage having one end of a flexible tube connected thereto, said tube being mounted in the bottom of the reservoir and extending upwardly therein and having a weighted head, whereby the tube will flex or bend when the jack is placed 45 in an inclined or horizontal position, thereby to retain the intake end of said flexible tube beneath the level of the fluid in the reservoir, and the fluid passage connecting the upper ends 50 of the reservoir and expansion tank having a passage having one end of a flexible tube connected thereto and extending downwardly into the expansion tank with its lower end terminating adjacent to the bottom of the expansion tank, whereby free circulation of the fluid between the reservoir and expansion tank is obtained without the use of an air vent.

TIMOTHY C. POMEROY.
